LIGHTWEIGHT REPEATING ROCKET LAUNCHER

Mitchell E. Bennett, Havre de Grace, Md., assignor to the United States of America as represented by the Secretary of the Army

Application July 1, 1953, Serial No. 365,567

7 Claims. (Cl. 89—1.7)

(Granted under Title 35, U. S. Code (1952), sec. 266)

The invention described herein may be manufactured and used by or for the Government for governmental purposes, without the payment to me of any royalty thereon.

This invention relates to improvements in lightweight repeating rocket launchers, and more particularly of the manually loaded magazine type.

It is the principal object of the invention to provide a launcher of the aforesaid type which is light in weight for the caliber of rocket to be launched, simple in construction and rapid and positive in operation.

It is a further object to provide a rocket launcher having a magazine adapted to hold at least one rocket for feeding by gravity into the firing tube when empty.

A still further object is to provide loading means operable by either the gunner or his assistant, whereby the launcher may be operated by one man or by a crew of two.

Numerous other objects will be obvious to those skilled in the art after a study of the following description in connection with the drawings.

In the drawings:

Figure 1 is a slide elevation of a launcher forming the subject of the invention.

Figure 2 is a top plan view of the launcher showing the loading mechanism in closed position;

Figure 3 is a similar view with the mechanism open;

Figure 4 is a partial cross section taken along lines 4—4 on Figure 2;

Figure 5 is a similar view taken along line 5—5 on Figure 3, and, Figure 6 is a cross sectional view taken along lines 6—6 in Figure 3.

Referring to the drawings, 1 indicates generally a rocket launcher having a firing tube 2 and an ammunition magazine indicated generally by numeral 3. A pair of vertically extending, axially spaced standards 4 and 5 are supported by the tube 2. These standards are connected at their upper portions by side panels 6 and 7 (Figure 6) which extend downwardly to a distance sufficient to leave side openings 8 and 9 for a purpose to be herewith described. There is thus formed a rectangular shaped chamber or magazine 10 which is of sufficient capacity to contain at least one rocket of the caliber fired by the launcher.

As shown at Figures 1 and 6 a portion of tube 2 between standards 3 and 4 is cut away to form an upwardly-facing loading opening 15. From Figure 1 it will be noted that the ends of this opening lie in axially-spaced parallel vertical planes each adjacent a respective one of the standards and that the side edges 15a and 15b, Figure 6, extend parallel with the axis of the tube and define an opening which extends through about 340° about the axis of the tube so that only a strip 15c is left rigidly connecting the muzzle and breech ends thereof.

The opening 15 is adapted to be closed, prior to launching of a rocket by a pair of substantially identical doors 11 and 12 each in the general form of a portion of a cylinder and each substantially equal in length to the

2

axial dimension of opening 15. These doors are journaled on respective hinge pins 13 and 14 secured at their ends in bosses or brackets affixed to the tube 2. Thus, referring to Figure 1, hinge pin 14 is fixed at its ends in bosses 14a and 14b secured by the tube walls. This pin journals the door 11 by means of a bracket 14c secured thereto, and in a relation obvious from inspection of Figure 6. Door 12 is hinged on pin 13 in a similar manner by bracket 13c.

5 By this construction when the doors are pivoted to the dotted line positions shown upon Figure 6, they completely close the loading opening 15 and form with the tube proper, a smooth-bore, continuous-walled launching tube. From Figure 6 it is noted that the doors are rabbed along their meeting edges as indicated at 13 to form a substantially gas-tight joint when closed. Rabbets or other sealing means not shown may likewise be used along the circularly-extending mating edges of the doors and opening.

10 20 Suitably spaced dogs 33 (Figure 6) pivotally mounted in opening in the side panel 7 are urged inwardly by springs 34 to bear against a rocket R to prevent its accidental upward movement.

The tube 2 may be provided at its lower surface with a pair of apertured ears 36 (Figure 1) to facilitate attachment of the launcher to a tripod, not shown. The launcher tube is provided with the usual grip 37 which incorporates a trigger 37a which, when pulled, operates miniature voltage generating means, not shown, in circuit with the contacts 16 and 17 which circuit is completed through the firing squib of the rocket when the latter is properly loaded with its contact band in engagement with contact 16. As this firing system is well known and forms no part of the present invention, it is not shown in detail.

25 30 35 As well shown in Figure 6, doors 11 and 12 are provided with planar extensions 19 and 18 respectively, which extend generally tangentially to their cylindrical surfaces upwardly from a line adjacent and parallel to their pivot axes. The upper edge of each extension is connected with the adjacent edge of its door by supporting surfaces 21 and 20, respectively, which are formed as portions of cylinders coaxial of the hinge axes of the respective doors. By this construction the two surfaces 20 and 21, when the doors are in closed position, jointly form a support for the lowermost rocket in magazine 10.

40 45 During initial opening of the doors, as surfaces 20 and 21 separate, the rocket is held in elevated position by reason of the coaxial feature of these surfaces. However, as the edges of the doors come in contact with the rocket, the latter is lowered at a gradually increasing rate. In the meantime, the lower portion of door 12 that is, the portion below hinge axis 13, is rising to its final open position shown in solid lines upon Figure 6, to form a cradle which is only a short distance vertically below the rocket when the latter is released from contact and support by the upper edges of the doors as they move into fully open position. Consequently, by the construction described the rocket is lowered smoothly and positively into firing position within this launcher when the doors are fully closed to form a launching tube open only at its ends. Firing contact 16 is carried by one end of a spring 16a whose other end is affixed to the door 11. The contact is yieldingly urged inwardly by the spring through an aperture 11b in the tube wall to make positive contact with a rocket loaded into the tube. The second or "hot" contact 17 mounted on, but insulated in any suitable way from the tube portion 15c engages the insulated firing band of the rocket when the latter is loaded whereby a firing circuit is completed in a manner well known in the art.

50 55 60 65 70 75 80 85 90 95

The loading doors are opened and closed by a system of linkage positioned forwardly and rearwardly of the magazine element. The forward linkage is generally indicated by numeral 22 (Figures 2, 3 and 4) and comprises an operating handle 23 connected at one end to the central portion of a bar 24 by a sleeve 25 and is pivotally mounted upon a reduced portion 26 of a boss 27 extending upwardly from and fixed with tube 2. It will be noted that this handle is positioned for convenient operation, either by the gunner or his assistant. It will be understood that in the closed position shown upon Figure 2, the handle 23 is swingable a little past dead center, so that the doors are self-locking, that is, so that the blast pressure of the rockets upon the doors cannot force them open. Suitable stop means not shown may be provided for limiting the rotation handle 23 in the direction of the arrow upon Figure 2 from a position slightly counterclockwise from the one shown.

Operation of the launcher is as follows:

Assuming that the doors are in closed position, the firing tube will now be a continuous smooth bore due to the doors 11 and 12 closing the aperture 15 and forming a part of the tube. A rocket may be inserted into the breech end of the tube and pushed forward until it is held by the indexing detent 16 at which time its insulated firing band will be in contact with the contact pin 17. A second rocket R may be placed in the magazine chamber 10. It will ride past dogs 33 and come to rest upon the arcuate portions 20 and 21 of the doors 11 and 12. The spring-biased dogs will hold the rocket firmly against sudden jolts which would otherwise cause upward motion thereof. After the rocket in the tube has fired, the second rocket R may be loaded into the firing chamber by the gunner or the assistant gunner by turning the handle 23 thru an arc of 180° clockwise as seen in Figure 2. Through the action of the linkage, the doors will open simultaneously and the rocket R will fall into the firing chamber and into position for firing. Turning the handle to the left through an arc of 180° will close the doors, so that the magazine may again be loaded and the rocket within the tube fired.

While the drawings illustrate space for one extra rocket only it is contemplated that it may be increased in height to accommodate several.

I have therefore provided a rocket launcher, relatively simple to operate, of lightweight and yet positive of action. The rate of fire is limited only by the rate at which rockets can be loaded into the magazine and the operating linkage actuated.

While the launcher as shown in the drawings is for manual operation, it may be operated by other means, not shown. It is also contemplated as a safety feature, that a switch contact on handle 23 may cooperate with a second contact carried by the launcher; to close the firing circuit to the loaded rocket only when handle 23 is in the fully closed position generally indicated at "L," Figure 2, whereby the doors must be fully closed and locked before a rocket can be fired.

A C-shaped link 28 has one end pivoted to one contiguous end of bar 24 while its opposite end is pivoted to the forward end of an arm 31 fixed to door 11 adjacent the area where surfaces 18 and 20 meet. Likewise a C-shaped link 29 is pivotally connected at one end with the other end of bar 24, while the remaining end of the link 29 is pivoted to an arm 30, corresponding to arm 31 and extending forward from door 12 in comparable position. From Figure 3 it is seen that links 28 and 29 face in opposite directions, and from Figure 5 that they are pivoted, one above bar 24 and the other below: Hence they do not interfere and operation of handle 23 between the limiting positions shown upon Figures 2 and 3 pivots the doors between the open and closed positions shown in solid and dotted lines, respectively, upon Figure 6. It will be understood that the pivot joints between links 28 and 29 and the arms 30, 31 may be of the ball and socket

type or may otherwise be formed to permit the necessary slight pivoted movement in the vertical planes through the links as the doors pivot between limiting positions.

The rear linkage, indicated generally at 32, is of similar construction with the front linkage just described except that handle 23 is omitted and a coil spring 43 added which is tensioned to urge link 40 to the fully closed position, that is, clockwise as viewed on Figure 3. Consequently it is sufficient to identify arms 38 and 39 and C-shaped links 41 and 42 connecting the same with the respective ends of bar 24. Arms 30 and 39 are in axial alignment as are arms 31 and 38.

Having now fully disclosed the invention, I claim:

1. A rocket launcher comprising a launcher tube having an upwardly-facing opening in its breech portion, magazine means fixed with said tube over said opening to receive and guide a rocket for downward loading into said tube through said opening, a pair of doors, means hinging each door on said tube at a respective side of said opening for pivotal movement about respective axes parallel with the axis of said tube from a first position closing said opening for firing a rocket from said tube, to a second position indexing a rocket from said magazine into said tube, each said door having a portion of a cylindrical surface coaxial of its hinge axis, said surfaces conjointly supporting a rocket in said magazine when said doors are in first position, the hinge axis of each door lying between the longitudinal side edges thereof, each said door having a portion of a cylindrical surface coaxial of said tube in closed position and pivotal about their respective axes to support an incoming rocket in said second position.

2. In a light-weight portable rocket launcher, a launcher tube having an upwardly-facing opening in its breech portion, a magazine fixed with said tube over said opening for receiving and guiding a rocket in gravity movement through said opening into said tube, first and second doors, hinge means pivoting said doors on said tube on respective axes at opposite sides thereof parallel with the tube axis to afford movement from a firing position wherein said doors conjointly close said opening, to an open position indexing a rocket into said tube, the hinge axis of each door lying between the side edges thereof whereby the lower portions thereof rise in response to pivotal movement of the doors to open position, each said door having a portion of a cylindrical surface coaxial of its hinge axis and conjointly supporting a rocket in said magazine when said doors are in firing position, whereby a rocket in said magazine is supported against downward movement until released by outward movement of said cylindrical surfaces when said doors have moved to open position whereby a rocket is indexed onto the raised lower ends of said doors.

3. In a rocket launcher, a launcher tube having an upwardly-facing loading opening, magazine means fixed with said tube in superposed position over said opening to guide a rocket downwardly through said opening into said tube, first and second doors hinged to respective sides of said tube for pivotal movement about axes parallel with said tube from a firing position wherein said doors conjointly close said opening, to a loading position effecting loading of a rocket into said tube, the hinge axes of each door lying between the side edges thereof whereby the portions of each door below its axis rises as the same moves to loading position, each said door having a portion of a cylindrical surface coaxial of its hinge axis and extending outwardly from its upper edge, said cylindrical portions conjointly acting to support a rocket in said magazine until the portions of the doors below their hinge axes have risen in loading movement, and means carried by said tube to effect synchronous movement of said doors between firing and loading positions.

4. A rocket launcher comprising a launcher tube having an upwardly-facing opening in its breech end, said opening having an angular extent about the axis of said

tube of about 340°, a magazine fixed with said tube in position superposed over said opening and adapted to receive at least one rocket for guided movement through said opening into said tube, first and second doors, means hinging each door to said tube at respective sides thereof for pivotal movement about axes substantially in the horizontal plane through the axis of said tube, for pivotal movement from a firing position wherein said doors conjointly close said opening, to a loading position wherein said doors effect movement of a rocket from said magazine through said opening into said tube, the hinge axis of each door lying between the side edges of the respective doors whereby the portions thereof below their pivot axes rise in response to pivotal movement to loading position, said first door having an angular extent below its axis greater than the corresponding extent of said second door, whereby to form a cradle portion receiving a rocket from said magazine, there being radially extending aperture therethrough, the upper edge of each said door having a portion of a cylindrical surface coaxial of its hinge axis and extending outwardly approximately 30°, said surfaces conjointly supporting a rocket in said magazine until said cradle has risen within said tube.

5. A rocket launcher as in claim 4, a firing control carried by said cradle portion, said firing control comprising a movable contact, and spring means urging said contact radially inwardly through said aperture in said cradle portion.

6. In a rocket launcher, a launcher tube having an upwardly-facing loading opening, magazine means fixed with said tube in superposed position over said opening, first and second doors hinged to said tube at respective sides of said opening for pivotal movement about respective axes parallel with the longitudinal axis of said tube from a firing position wherein said doors conjointly close said opening to a loading position wherein said doors index a rocket from said magazine means through said opening into said tube, each said door having a surface in the form of a portion of a cylinder coaxial of its hinge axis for supporting a rocket against substantial downward

movement in said magazine until said doors have moved out of firing position, the hinge axis of each door lying between its longitudinal edges whereby the lower portion of each door rises within said tube as the doors move toward loading position, and a single manually controlled means for simultaneously pivoting said doors between loading and firing positions and locking the same in firing position.

7. In a rocket launcher, a launcher tube having an upwardly-facing loading opening, magazine means fixed with said tube in superposed position over said opening, first and second doors hinged to said tube at respective sides of said opening for pivotal movement about respective axes parallel with the longitudinal axis of said tube from a firing position wherein said doors conjointly close said opening to a loading position wherein said doors index a rocket from said magazine means through said opening into said tube, each said door having a surface in the form of a portion of a cylinder coaxial of its hinge axis for supporting a rocket against substantial downward movement in said magazine until said doors have moved out of firing position, said first door having an angular extent below its axis greater than the corresponding extent of the second door, whereby the lower portion of said first door when in loading position acts as a cradle to receive a rocket from said magazine when released from said surface, and a single manually controlled means for simultaneously pivoting said doors between loading and firing positions and locking the same in firing positions.
